[57] CLAIM

The ornamental design for a clothes hook, as shown and described.

DESCRIPTION

FIG. 1 is a front perspective view of a clothes hook
showing our new design;

FIG. 2 is a front elevational view thereof;

FIG. 3 is a right side elevational view of a first embodiment,
the left side elevational view being a mirror image;

FIG. 4 is a rear elevational view thereof;

FIG. 5 is a top plan view thereof;

FIG. 6 is a bottom plan view thereof;

FIG. 7 is a rear elevational view of a second embodiment, having an appearance substantially the same as the embodiment of FIGS. 1-6, except for a change in the rear face; and,

FIG. 8 is a bottom plan view of the embodiment of FIG.
